UNITED STATES PATENT OFFICE

FRED L. MILLS, OF OAK PARK, ILLINOIS, ASSIGNOR TO MILLS NOVELTY COMPANY, OF CHICAGO, ILLINOIS, A CORPORATION OF ILLINOIS

VENDING MACHINE

Application filed May 4, 1929. Serial No. 360,367.

This invention relates to vending machine and more particularly to such machines adapted for use at homes, apartment buildings and like places for dispensing staple articles, the invention being in the nature of an improvement or supplement to the invention of my co-pending application, Serial No. 360,366, filed May 4, 1929.

As set forth in said co-pending application, 10 the machine requires for the operation thereof the use of both a key and a coin and due to the fact that the keys will be in the hands of only certain known persons, the responsibility can be traced to them in case a slug is 15 used instead of a bona fide coin to operate the machine. In this way the possibility of loss to the vendor through the use of slugs in operating the machine is reduced to a minimum or completely eliminated. It may be, 20 however, that when the machine is used at the rear of an apartment building it will be patronized by a number of individuals living in the apartment, each of whom would be provided with a key, and while it would be 25 possible to confine the responsibility for the use of slugs to those who were provided with keys, it would not be possible to fix the blame upon a particular one of such individuals since any one of them might operate the machine and it would not be possible to tell 30 which of them inserted the slug. In accordance with the present invention, the coin box for receiving the coins used in operating the machine is divided into a number of different compartments, and a device is provided for directing the coins into one or another of said compartments according to the 35 particular key used.

In this scheme of operation, the keys furnished the different persons who are to patronize the machine will differ, preferably as to length, and the individual keys will serve to move a swiveled hopper or like means into registration with a compartment of the coin box particularly associated with the key employed. In this way, if a slug is found in any particular compartment of the coin box, the responsibility for inserting it may be traced to the individual who has the key 50 which serves to arrange the hopper in posi-

tion for directing the coin or slug into that compartment.

Other objects and advantages of the invention will be apparent as it is better understood from the following description, which, taken in connection with the accompanying drawings, discloses a preferred embodiment thereof.

Referring to the drawings,

Fig. 1 is a front elevation of a machine in which my invention is embodied, certain parts thereof being broken away for convenience in illustration;

Fig. 2 is a front to back section of said machine;

Fig. 3 is a plan view taken substantially on the plane 3—3 in Fig. 1;

Fig. 4 is a perspective view of the latching mechanism; and

Fig. 5 is a view of the key employed in conjunction with a coin for operating the machine, said view showing in dotted lines how the actuating lugs on different keys may be varied in length for the purpose hereinbefore explained.

The machine, as thus illustrated, comprises a casing 21 in which there is a series of compartments 22, these being arranged in the particular embodiment shown in two tiers and each compartment being adapted to contain a single package of the commodity to be sold. Each compartment is provided with a door 23 which has a central glass panel 24 through which the package 25 may be viewed.

Each door is equipped with a latch, which is shown in detail in Fig. 4, said latch comprising a bell crank member 26 which is pivoted at 27 to a frame part 28, one arm 29 of said bell crank extending forwardly through a slot 31 in the front 32 of the casing and the other arm 33 of said bell crank extending upwardly and carrying a stud 34 at the end thereof, said stud being normally in engagement with the side of a bar 35 shown fragmentarily in said Fig. 4 and more fully in Figs. 1 and 2. A laterally extending lug 36 is provided upon said upper arm 33 of the bell crank and is adapted to be normally disposed in a notch 37 in a keeper 38 secured to the interior of the door by means of rivets 100.

39. Springs 41 secured at one end of the latching lugs 36 on the bell crank members 26 and at the other end to the side of the casing serve to hold the studs 34 of the latching members against the side of the bar 35.

Said bar 35, as best shown in Fig. 1, is provided with a series of notches 43 in the edges thereof, said notches being adapted to be successively brought into registration with the 10 studs 34 of the several latching devices, as will presently appear. When so brought into registration, the stud 34 is permitted to enter the notch, thereby permitting the latching lug 36 to be disengaged from the keeper 15 38 and allowing the door to be opened, a knob 44 being provided on the exterior of the door for this purpose, if desired.

The bar 35 is provided with a series of notches shown at 45 at the bottom of Fig. 1, 20 and a control member or finger 46, which is pivoted at 47 to a supporting plate or bracket 48 on the interior of the casing, is provided to hold said bar in raised position, said control member or finger being provided with a 25 hooked portion 49 at the lower end thereof which is urged toward said bar 35 and into one of the notches 45 by means of a spring 51 which is wound around a stud 52, being secured at one end as indicated at 53 and the 30 other end thereof bearing against a lug 55 on the upper end of said member 46, urging the latter in clockwise direction about the pivot 47. Said member 46 is provided with an arm 56 extending laterally from the upper 35 end thereof into a coin chute indicated by the reference character 57. Said coin chute leads upwardly to a coin slot 58 and a stud 59 is provided in the lower part of said coin chute to obstruct the passage of a coin 61 40 when the latter is dropped into the slot. The position of the coin, as shown in full lines in Fig. 1, is such that it is held between the arm 56 of the member 46 and a bolt 62 of a key lock 63, the bolt being adapted to be moved 45 toward the left in said Fig. 1 by the turning of a key in said lock in manner which will be readily understood. Such action tends to move the coin toward the left in said Fig. 1, turning the member 46 on its pivot to cause 50 the same to disengage the bar 35, permitting the latter to drop until re-engaged by the member 46 which enters the next notch 45 after the coin has passed down the coin chute, as shown in dotted lines in Fig. 1.

55. The first coin inserted causes the bar to drop only sufficiently to permit actuation of the latch for the compartment shown at the lower left in Fig. 1, it being noted that the notch 43 in said bar 35 for this compartment is longer than the remaining notches and extends lower than the corresponding notch for the compartment at the right on the same plane with said first-mentioned compartment. The notches for the compartments 60 above are similarly arranged in staggered re-

lationship and successively decrease in length so that one compartment after another may be successively opened, and after the bar is dropped to the lowermost position, or at any time for that matter, an authorized person having access to the machine through a normally locked side door 63 may raise said door to the uppermost position, thereby locking the compartments which have been opened, it being understood that they would be refilled before being locked.

70 It will be observed that it requires the joint use of a key and a coin to actuate the member 46 so that in case a slug is inserted it will be known that it was used by someone 75 having possession of a key. In order that the particular person using the slug may be identified, however, I provide a device shown in the lower part of Fig. 2 and in Fig. 3, whereby the coin or slug will be directed into one or another of a series of compartments 65 provided in a coin box indicated generally at 66, according to the particular key used, the keys furnished to different persons authorized to patronize the machine being of different length and each adapted to actuate the device just mentioned in such way as to direct the coin or slug to a particular compartment which may thus be identified with the key used. The key, which is indicated by the reference character 67, is provided with a lug 68 at the end thereof, which may be of varying length, as indicated by dotted lines in Fig. 5, the inner end of the key being adapted to protrude through the lock cylinder 63 and to engage a member 69 pivoted at 71 to an upright 72 and connected by a link 73 with an arm 74 rigid with a swiveled hopper 75 which is pivoted to said upright 72 and has a flaring mouth portion 76 into which the lower end 77 of the coin chute 57 extends, said hopper narrowing toward the bottom and the lower part thereof being adapted to be arranged in registration with one or another of a series of guideways 78, 80 one of which is provided for each of the compartments 65 of the coin chute, which compartments correspond in number to the 85 number of commodity compartments provided in the casing 21.

90 A counter-weight 79 is provided on the arm 74 to hold the hopper 75 normally in registration with the passageway 78 at the left in Fig. 2, the lower end of the hopper being moved toward the right to a greater or less extent according to the length of the key employed and thus brought into registration with any one of the passageways 78, the particular one being determined by the length 95 of the lug 68 on the key.

100 It is thought that the invention and many of its attendant advantages will be understood from the foregoing description, and it will be apparent that various changes may 105 be made in the form, construction and ar- 110

rangement of the parts without departing from the spirit and scope of the invention, or sacrificing all of its material advantages, the construction hereinbefore described being merely a preferred embodiment thereof.

5 I claim:

1. A vending machine comprising a commodity container, locking mechanism therefor requiring the use of both a key and a coin 10 for the operation thereof to unlock the container, a coin box having a plurality of compartments therein, and means operable by the key to direct the coin used in the operation of said locking mechanism into one or 15 another of the compartments in said box according to the length of the key employed.
2. A vending machine comprising a commodity container, locking mechanism therefor requiring the use of both a key and a coin 20 for the operation thereof to unlock the container, a coin box having a plurality of compartments therein, and means operable by the key to direct the coin used in the operation of said locking mechanism into one or 25 another of the compartments in said box according to the particular key employed, the lock being adapted to receive different keys.
3. A vending machine comprising a commodity container, locking mechanism therefor 30 requiring the use of both a key and a coin for the operation thereof to unlock the container, a coin box having a plurality of compartments therein, and means operable by the key to direct the coin used in the operation 35 of said locking mechanism into one or another of the compartments in said box according to the particular key employed, the lock being adapted to receive keys of different length.
4. A vending machine comprising a commodity container, locking mechanism therefor 40 requiring the use of both a key and a coin for the operation thereof to unlock the container, a coin box having a plurality of compartments therein, and means comprising a swiveled hopper operable by the key to direct the coin used in the operation of said locking mechanism into one or another of the compartments in said box according to 45 the particular key employed, the lock being adapted to receive different keys.
- 50 In witness whereof, I hereunto subscribe my name to this specification.

FRED L. MILLS.
